UNITED STATES PATENT OFFICE.

JOSEPH MAGYAR, OF PURITAN, PENNSYLVANIA.

LIFE-PRESERVER.

1,093,002.

Specification of Letters Patent. Patented Apr. 14, 1914.

Application filed November 22, 1913. Serial No. 802,475.

To all whom it may concern:

Be it known that I, JOSEPH MAGYAR, a subject of the King of Hungary, residing at Puritan, in the county of Cambria and State of Pennsylvania, have invented certain new and useful Improvements in Life-Preservers, of which the following is a specification.

This invention relates to life preservers.

10 An object of the invention is to provide a life preserver which shall be simple in construction, easily applied to use, and when *in situ* will be thoroughly effective in supporting the weight of a human body in the water in an upright position, whereby all danger of being overswept by waves will be eliminated.

20 A further object is to provide an apparatus of this character which may be worn without discomfort to the wearer but which, when necessity compels, may be brought to a condition in which the user will be effectively guarded against any danger of drowning under any but exceptional contingencies.

25 With the above and other objects in view, as will appear as the nature of the invention is better understood, the same consists, generally stated, in a life preserver embodying, in its construction, a pair of trousers adapted 30 to be worn by either sex, the waist of which is extended to include the chest up to as far as the arm pits, there being combined with the trousers a pair of weighted shoes that will insure the maintenance of the wearer in a vertical position, and through an inflatable water-proof bag which may be distended by air pressure, to such an extent as to insure the absolute floating of the wearer, and his maintenance above the crests of waves, so 40 that danger of drowning will be reduced to a minimum.

35 In the accompanying drawing forming a part of this specification, and in which like characters of reference indicate corresponding parts: Figure 1 is a view in front elevation of a human figure showing the same equipped with the apparatus constituting the present invention. Fig. 2 is a horizontal sectional view taken on the line 2—2, Fig. 1, 45 and looking in the direction of the arrow thereon.

40 The apparatus consists of a pair of trousers, which may be constructed of any suitable material, water-proof, or otherwise, and 50 having the waist 1 extended above the crotch to such a distance as to include all of the

chest up to the arm pits. The upper portion of the waist is slotted and is provided with a two-part belt 2 connected by a buckle 3, this arrangement permitting what might be 60 termed the belt portion designated by 1 to be securely fastened around the body of the wearer. The legs 4 have secured to their lower ends shoes 5 which are preferably of rubber, and have sole weights 6 which will be 65 of such weight as to maintain the body of the wearer in vertical position in the water.

Surrounding the trousers, and extending from the crotch to a point below the upper edge of the waist is an inflatable bag 7, 70 which is constructed of any suitable water-proof material, and is provided at its upper end with a band 8 that is secured to the waist of the trousers and at its lower end with two bands 9 that are similarly secured to the 75 legs 4, the union between the parts 1 and 4 being accomplished preferably by stitches, although if preferred, an adhesive may be employed. It will be understood that the bag 7 has an inner wall 10 defining an air 80 chamber 11, there being therefore, no communication between the bag and the trousers.

As a means for inflating the bag 7, a flexible tube 12 is provided, one end of which is connected in any suitable manner with the 85 bag, and the other end of which is provided with a mouth piece 13 including an inward opening valve (not shown) which will permit ingress but prevent egress of air. This mouth-piece normally engages a keeper 14 90 secured to the upper portion of the waist, so as to be in easy reach of the user.

As will be obvious, there will be a tendency for the lower portion of the trousers legs to bag, and to prevent this, each leg is 95 provided near the shoe top with an adjustable band 15, which may be tightened to secure the object sought.

In use, in the event of a collision at sea, the suit or preserver will be donned with the 100 bag 7 in the deflated condition. It may thus be worn until the contingency arises that the passengers must leave the ship, and in this event, the wearer will remove the mouth-piece from the keeper 14 and inflate the bag. 105 Owing to the fact that the only addition to an ordinary garment is the bag, it will be apparent that the use of the apparatus will not in any way incommod the wearer while the bag is in deflated condition.

110 From the foregoing description, it will be seen that although the structure of the

present invention is exceedingly simple in construction, it will be thoroughly effective for the object sought, and will, if properly used, result in the absolute saving of life except under unprecedented conditions.

What I claim as new is:—

A life preserver comprising a pair of trousers, a water-proof inflatable bag secured around the waist and crotch portions

of the trousers, and shoes secured to the bottoms of the trousers legs.

In testimony whereof I affix my signature in presence of two witnesses.

JOSEPH MAGYAR.
